UNITED STATES PATENT OFFICE.

PETER A. KUHN, OF LYNDHURST, NEW JERSEY.

DESIGN FOR A SURF-CHAIR.

SPECIFICATION forming part of Design No. 24,038, dated February 12, 1895.

Application filed December 14, 1894. Serial No. 531,865. Term of patent 3½ years.

To all whom it may concern:

Be it known that I, PETER A. KUHN, a citizen of the United States, residing at Lyndhurst, Bergen county, in the State of New Jersey, have invented a certain new and original Design for a Surf-Chair, of which the following is a description, reference being had to the accompanying drawings, which form a part of this specification.

Figure 1 is a plan view, and Fig. 2 is an end elevation.

The leading feature of my design consists in the unitary article presenting the appearance of two bodies of cylindrical form, joined together by a downwardly projecting curved portion, the lines of which flow tangentially into the circular outlines of the bodies.

Similar letters of reference indicate the same parts in both the figures.

A, A, are the cylindrical portions, and A' the depending curved portion connecting them to each other, the whole presenting in end view the appearance of two circles joined by a hanging loop, the lines of which flow gracefully into the outlines of the circles. The cylindrical portions A, A, and the curved portion A' are of openwork in the form of narrow slats laid close together parallel with the axes of the cylindrical portions, as shown, giving to the whole an appearance of lightness.

I claim—

The design for a surf chair herein shown and described.

PETER A. KUHN.
